PER Munro.

United States Patent Office.

E. L. ROBERTS, OF BROOKLYN, NEW YORK.

Letters Patent No. 93,007, dated July 27, 1869.

VENTILATING-APPARATUS.

The Schedule referred to in these Letters Patent and making part of the same.

To all whom it may concern:

Be it known that I, E. L. ROBERTS, of Brooklyn, in the county of Kings, and State of New York, have invented a new and improved Ventilating-Apparatus; and I do hereby declare that the following is a full, clear, and exact description thereof, which will enable others skilled in the art to make and use the same, reference being had to the accompanying drawings, forming part of this specification.

This invention relates to improvements in ventilating-apparatus for buildings, and has for its object to provide a simple and efficient arrangement of passages, heater, and valve-device, which, while governing the volume of air admitted, either to cause it to pass into the room through a cold-air passage, or through a passage bringing it into contact with a heater, will always admit a full volume of air, thereby keeping up the maximum degree of circulation, the arrangement being such that a movement of a single hand-crank, or other valve-operating device, effects the necessary valve-adjustment for causing the air to pass in either direction, all as hereinafter more fully specified.

Figure 1 represents a sectional elevation of a part of a building, with my improved apparatus applied to it, the section being taken on the line *x x* of fig. 2;

Figure 2 represents a sectional elevation of the same, taken on the line *y y* of fig. 1; and

Figure 3 represents a sectional elevation of a modified arrangement of the said improved device.

Similar letters of reference indicate corresponding parts.

This invention is more especially adapted to be used in connection with a method of ventilating and heating, such as heretofore patented to me, in which the air is conveyed from the level of, or below the level of the floor of a room, into the same through the ceiling or the sides near the ceiling. It is also applicable to other similar methods.

In the common arrangement of heating and ventilating-apparatus, the hot air is supplied through one conductor or register, and cold air by another, each separate and independent of the other, requiring attention to two sets of valves or registers for properly regulating the air, between which there can be no uniformity of action, and consequently the flow of air may at times be wholly cut off from both sources, or wholly admitted from both, from which deleterious results will obviously follow.

My invention contemplates a uniform and constant flow of air through the room, adapted to the capacity of the same at all times, and capable of variation as to temperature by a simple movement of a valve.

In the drawing—

A represents the interior of the room, to be supplied with air through the top, and exhausted through the

bottom, according to the method described in the patent to me, above alluded to.

B represents the shaft or passage for the air from below to the space *C* above the ceiling, from which it passes into the room.

When the natural temperature of the air is such as not to be uncomfortable to the occupants of a room, it is designed to be caused to pass in without contact with a heater, and then passes, according to my improved arrangement, under the valve *D*, at *C'*, but if required to be heated, it is required to pass up along the heater *E* through the space *F*.

This valve *D* is intended for closing one passage and opening the other simultaneously, by a movement in one direction, and *vice versa*, and is suspended by a chain, *G*, or otherwise from a winding-shaft, *H*, the stem of which projects into the room.

By this simple arrangement, the air passing in at the mouth *I*, at the base of the shaft, may be caused to pass over the heater or not, as required, or a part may pass one way and a part the other, in any required proportions, according to the temperature of the external air and that required in the room, and this regulating is accomplished by the movement of one valve only, and so as to always maintain the same area of opening, and consequently the same measure of air and degree of activity thereof.

The passage *H* is intended to admit the measure of air constantly required.

I may apply this plan of arrangement under various modifications, as it may be found most desirable to arrange the air-passages and heater, one example of which is shown in fig. 3, wherein the cold-air passage to the shaft *B* is at *K*, while that which passes over the heater enters at the passage *I*, and the valve is made in two parts *D'* and *D''*, and suspended from a pulley or pulleys *L*, capable of oscillation, to wind the chains either way, and having a stem for operating it passing through the wall to the room.

Instead of sliding valves, the ordinary registers may be used, by connecting the cords or chains so as to open or close the slats thereof.

Having thus described my invention, I claim as new, and desire to secure by Letters Patent—

The arrangement of cold and hot-air passages, heater, and valve-devices for opening the one passage and closing the other, and *vice versa*, simultaneously, by one and the same movement of the valve-apparatus, substantially as specified.

The above specification of my invention signed by me, this 27th day of May, 1869.
